UNITED STATES PATENT OFFICE.

WALTER W. McCASKIE, OF HIBBING, MINNESOTA, ASSIGNOR OF ONE-HALF TO BYRON K. DUTTON, OF HIBBING, MINNESOTA.

STOKER.

1,323,401.

Specification of Letters Patent.

Patented Dec. 2, 1919.

Application filed June 2, 1919. Serial No. 301,244.

To all whom it may concern:

Be it known that I, WALTER W. McCASKIE, a citizen of the United States of America, and resident of Hibbing, in the 5 county of St. Louis and State of Minnesota, have invented certain new and useful Improvements in Stokers, of which the following is a specification.

This invention relates to stokers and particularly to means for insuring proper delivery of fuel or coal to the said stoker.

In stokers having hoppers containing coal which is delivered from the hopper to the stoker, the coal often becomes banked or so 15 packed in the hopper as to remain therein, notwithstanding the stoker feeding mechanism is in operation. In other words, the said coal becomes arched so that there is a space under the mass of coal in which the 20 stoker feeding mechanism is operating without coming in contact with the coal, hence the furnace is imperfectly supplied with fuel.

It is an object of this invention to provide 25 means for dislodging coal and for agitating it in the hopper so that it will not become banked in the manner stated, and it is furthermore the purpose by the mechanism to insure uniformity of feed while the stoker 30 feeding mechanism is in operation.

With the foregoing and other objects in view the invention consists in the details of construction, and in the arrangement and combination of parts to be hereinafter 35 more fully set forth and claimed.

In describing the invention in detail, reference will be had to the accompanying drawings forming part of this specification wherein like characters denote corresponding parts in the several views, and in which—

Figure 1 illustrates a view in elevation of the feeding and agitating mechanism embodying the invention;

Fig. 2 illustrates a top plan view thereof;

Fig. 3 illustrates an end view of the mechanism with the hoppers shown in dotted lines;

Fig. 4 illustrates a sectional view of a shaft with the blade applied thereto; and

Fig. 5 illustrates a sectional view of said shaft having another form of blade attached thereto.

In these drawings 10 denotes the hopper

or bin to which the coal is supplied for delivery by the stoker mechanism which 55 stoker mechanism is embraced within or associated with a casing 11.

A shaft 12 is rotatably mounted in known manner with respect to the bin or hopper 60 and the said shaft is supplied with a plurality of coal agitating blades 13 secured to the shaft 12 by clips 14 and the said shafts are further supplied with blades 15 and 16 forming extensions of a clip member, 65 which clip member partially embraces the shaft 12 and is held in place by a clip member 18 which partially embraces the shaft and is secured to the clip member 17 by fastenings 19, such as bolts. 70

As the shaft 18 partially rotates, the blades 13, 15 and 16 oscillate and are intended to dislodge coal and cause it to be delivered to the stoker 11, the said shaft being partially rotated through the medium 75 of an arm 20 secured to the shaft and adjustably connected to a section of a link 21 which has an adjustment at 22. The link further has an adjustment by means of the apertures 23 in the arm so as to increase or 80 diminish the throw of the arm and the movement of the shaft.

The link 21 has an end connected by a wrist pin 24 to a crank or arm 26 secured on the stoker operating shaft 27, so that as 85 the stoker operating shaft rotates, the link or pitman 21 reciprocates and oscillates the arm 20 so that the blades 13, 15 and 16 oscillate in an arc of a circle.

Near each end of the shaft 12 a blade 13 has a pivot 28 to which an arm 29 of a scraper 30 is connected and the said scraper is intended to move up and down the wall 90 of the hopper near the corner to prevent the packing and lodgment of coal at the corners as those are the points where it is more apt to lodge. The form of the scrapers is well shown in Figs. 1 and 2 of the drawing, and the said scrapers are guided by U-bolts 31 extending through the wall of the hopper 100 and secured in place by fastenings such as nuts 32.

From an inspection of the drawing and from the foregoing description, it will be apparent that as the stoker operates to feed 105 coal, coal is delivered to the stoker or is agitated so as to gravitate to the stoker by reason of the mechanism heretofore de-

scribed, which mechanism is operated simultaneously with the stoker so that so long as coal remains in the hopper or bin, it will be caused to gravitate to the stoker.

5 I claim—

1. In a coal feeding mechanism, a hopper for delivering coal to a stoker, a shaft, means for operating the shaft, a coal agitating means comprising a shaft, blades 10 mounted on the said shaft, pivots carried by certain of said blades, scraper arms mounted on the pivots, scrapers carried by the arms, means actuated by the stoker operating mechanism for partially rotating the

shaft in opposite directions alternately, and 15 means for guiding the scraper arms.

2. In a coal feeding mechanism, a hopper for delivering coal to a stoker, a shaft, means for operating the shaft, coal agitating means comprising a shaft, blades mounted on the said shaft, pivots carried by certain of said blades, scraper arms mounted on the pivots, scrapers carried by the arms, and means actuated by the stoker operating mechanism for partially rotating in opposite 20 directions alternately.

WALTER W. McCASKIE.
